Inventor
Ellis Earnshaw,

UNITED STATES PATENT OFFICE.

ELLIS EARNSHAW, OF GRAFTON, MASSACHUSETTS, ASSIGNOR OF ONE-HALF
TO GEORGE W. FISHER, OF SAME PLACE.

SHUTTLE-BINDER FOR LOOMS.

SPECIFICATION forming part of Letters Patent No. 408,470, dated August 6, 1889.

Application filed May 22, 1889. Serial No. 311,677. (No model.)

To all whom it may concern:

Be it known that I, ELLIS EARNSHAW, a citizen of the United States, and a resident of Grafton, in the county of Worcester and State 5 of Massachusetts, have invented a new and useful Improvement in Shuttle-Binders for Looms, of which the following is a specification, reference being had to the accompanying drawings, representing such portions of a 10 loom as embody my invention, and in which—

Figure 1 represents a top view of one end of the lay, showing the shuttle-box. Fig. 2 is a front view of the same, and Fig. 3 is a sectional view of a portion of the shuttle-binder 15 and stud upon which the binder is hinged.

Similar letters refer to similar parts in the different figures.

My invention relates to the lay of a loom; and it has for its object to secure a uniform 20 and regular action of the shuttle, and also to cause the protector-finger to be moved uniformly by the motion of the binder; and my invention consists in the improved manner of hinging the binder to the lay, as fully described hereinafter, and specifically set forth 25 in the subjoined claims.

In the accompanying drawings, A denotes a portion of the lay; B, the shuttle-box; C, the binder, hinged at one end to the lay. D 30 denotes the binder-spring. E is the protector-finger, attached to a protector-rod F, and having its free end resting against the free end of the binder C. A torsional spring G is applied to the rod F to hold the finger E against 35 the binder C.

The construction and operation of the parts above described are common to weaving- 40 looms, and will therefore be well understood without detailed description.

As the shuttle is driven into the shuttle-box by the picking mechanism of the loom, it is brought into contact with the inner convex side of the binder, carrying the free end 45 of the binder outward, moving the finger E, and slightly rocking the rod F in the usual and well-known manner. The frictional contact of the binder upon the shuttle holds the shuttle from any rebound as it enters the box, and it is important that this frictional 50 adhesion should be regular and uniform in

order that a uniform resistance shall be offered to the force of the picking mechanism. It is also necessary that the swinging motion of the binder upon its pivotal stud be uniform in order to secure the uniform rocking motion of the protector-rod by means of the protector-finger E. The pressure of the binder-spring D is applied near the central section of the binder at a, and as the inner end b of the binder is held by the force of the 55 spring applied to the protector-rod the action of the shuttle as it is thrown into the box will tend to carry the hinged end of the binder outward, and any lost motion caused by the wear of the binder upon the pivotal 60 stud will be constantly increased by the operation of the loom, causing the hinged end of the binder to yield, thereby reducing the motion of the end b of the binder and decreasing the rocking motion of the rod F. 65 The yielding of the hinged end of the binder will also vary the pressure of the binder-spring upon the shuttle, and consequently vary the resistance of the shuttle to the picking mechanism of the loom. 70

The inner side of the binder should present a true vertical wall to the contact of the shuttle, and in case the binder or its pivotal stud becomes irregularly worn the binder is often allowed to tip and bear against the corner of 75 the shuttle.

To secure the regular and uniform action of the binder is the object of my present invention, and this object I accomplish by means of the mechanism shown in the drawings and 80 hereinafter described.

In place of the ordinary stud now in common use, upon which the binder is hinged and which passes through a hole in the outer end of the binder, I employ a hollow stud H, 90 provided with a flange I and attached to the lay by means of a nut J upon the screw-threaded section K of the stud, in the usual manner in which the binder-studs are now attached to the lay. The stud H is provided 95 with the longitudinal concentric chamber L. The end c of the binder is bored to receive the hollow stud H, forming a chamber M, which extends partly through the binder, and in the end wall N of the chamber M, I place 100

- the pin O, rigidly attached to the binder and concentric with the chamber M, the pin O fitting the concentric chamber L in the stud H. I thereby secure a double bearing-surface of 5 the binder upon the outside of the stud H and of the pin O in the concentric chamber L. The bottom of the chamber L also serves to contain oil or lubricating material, which is kept from being thrown by the swing of the 10 lay upon the woven fabric or upon the shuttle by means of the end of the binder, which forms a cap over the end of the hollow stud H. A thorough lubrication of the bearing is thus secured, which would not be possible 15 with a bearing open at the top, as the centrifugal force at each swing of the lay would cause the lubricating material to be thrown out of the bearing. It will usually be found sufficient to lubricate the binder-bearing only 20 at the insertion of a new warp, when the binder can be readily lifted from the hollow stud H by removing the free end of the binder-spring C from off the binder.
- The pin O is provided with a shoulder *d*, 25 which rests upon the end *e* of the stud H, forming a bearing to receive the downward pressure of the binder C, rendering it more durable, as the pin and stud can be made of steel.
- 30 What I claim as my invention, and desire to secure by Letters Patent, is—
1. The combination, with the lay of a loom, of a stud attached to said lay and forming a pivot upon which the binder is hinged, said 35 stud being provided with an interior chamber to contain lubricating material, and a binder

hinged upon said stud, the hinged end of said binder having a chamber to receive said stud and forming a cap over the end of said stud, in order to prevent the lubricating material 40 from being thrown at each swing of the lay, substantially as described.

2. The combination, with the lay of a loom, of a stud attached to said lay and provided with a longitudinal concentric chamber open 45 at the upper end of the stud, a binder hinged upon said stud and provided with a chamber fitting said stud, and a pin held in said chamber and concentric therewith and fitting the chamber in the stud, substantially as de- 50 scribed.

3. The combination, with the lay of a loom, of a stud attached to said lay and provided with a longitudinal concentric chamber open 55 at the upper end of the stud, a binder hinged upon said stud, a pin held in said binder fitting the chamber in said stud and provided with a shoulder resting upon the upper end of the stud, substantially as described.

4. The combination, with the lay of a loom, of stud H, having a chamber L, binder C, pin O, held in said binder and fitting the chamber L, and having shoulder *d* resting upon the end *e* of the stud H, said binder having a chamber M fitting the stud H, substantially 60 as described.

Dated this 18th day of May, 1889.

ELLIS EARNSHAW.
